UNITED STATES PATENT OFFICE.

LE ROY B. FRASER, OF WOODBRIDGE, CONNECTICUT.

DESIGN FOR A TOY WINDMILL.

Application filed November 14, 1924. Serial No. 11,379. Term of patent 3½ years.

To all whom it may concern:

Be it known that I, LE ROY B. FRASER, a citizen of the United States, residing at Woodbridge, in the county of New Haven and State of Connecticut, have invented a new, original, and ornamental Design for a Toy Windmill, of which the following is a specification, reference being had to the accompanying drawings, forming part thereof.

Figure 1 is a perspective view of a toy windmill embodying my invention.

Figure 2 is a plan view of the same.

I claim:

The ornamental design for a toy windmill as shown.

LE ROY B. FRASER.

Witnesses:

FREDERIC C. EARLE,
MALCOLM P. NICHOLS.
